DESIGN FOR A NASAL PROTECTOR FOR BATHERS

Maxwell Vernon Smith, Weehawken, N. J.

Application October 26, 1943, Serial No. 111,500

Term of patent 14 years

To all whom it may concern:

Be it known that I, Maxwell Vernon Smith, a citizen of the United States and resident of Weehawken, New Jersey, have invented certain new, original, and ornamental Design for a Nasal Protector for Bathers, of which the following is a specification, reference being had to the accompanying drawing, forming part thereof:

with the neck band broken away to illustrate indeterminate length;

What I claim is:

The ornamental design for a nasal protector for bathers, substantially as shown.

MAXWELL VERNON SMITH.
